LAMP CORD SWITCH

Herbert G. Lehmann, 5 Kent Road,
Easton, Conn. 06612

Filed Apr. 30, 1970, Ser. No. 22,724

Term of patent 14 years

Int. Cl. D13—03

U.S. Cl. D26—13

Fig. 1

Fig. 5

Fig. 2

Fig. 4

Fig. 3

FIG. 1 is a top plan view of a lamp cord switch, embodying my new design.

FIG. 2 is a side elevational view of a lamp cord switch, the opposite side being a mirror image of the side shown.

FIG. 3 is a bottom plan view of the lamp cord switch.

FIG. 4 is a right end elevation of the lamp cord switch.

FIG. 5 is a left end elevation of the lamp cord switch.

I claim:

The ornamental design for a lamp cord switch, as shown and described.
